Charles R. Searle,

UNITED STATES PATENT OFFICE.

CHARLES M. ROSE, OF NEW YORK, N. Y.

NOTIFICATION-TABLET.

1,182,318.

Specification of Letters Patent.

Patented May 9, 1916.

Application filed September 8, 1915. Serial No. 49,432.

To all whom it may concern:

Be it known that I, CHARLES M. ROSE, a citizen of the United States, residing in the city of New York, borough of Manhattan, 5 in the county and State of New York, have invented a certain new and useful Improvement in Notification-Tablets, of which the following is a specification.

In cases of fire, burglary, or other accident, it frequently happens that the residence addresses of owners of the premises affected cannot be learned by the firemen or police and considerable time elapses before such owners or other interested parties receive information of the occurrence and are able to arrange for the protection of property thus exposed. This is notably the case in night fires in large office or loft buildings in which a number of rooms or floors are 15 often broken open by the firemen in locating and fighting the fire.

The object of this invention is to provide a conspicuous tablet preferably located on or near the door, containing the addresses 25 of the parties to be notified immediately in the event of such occurrence.

A further object is to provide means for protecting such addresses from dust and smoke and also for concealing them under 30 ordinary conditions while inviting easy access when desired in an emergency, and another object is to provide means whereby such addresses may be exposed by manipulation from the outer face of the door before 35 forcible entrance is effected.

The invention consists in certain novel features and details of construction and arrangement by which the above objects are attained, to be hereinafter described and 40 claimed.

The accompanying drawings form a part of this specification and show an approved form of the invention.

Figure 1 is an elevation of a portion of the 45 inner face of a door having the tablet thereon. Fig. 2 is a corresponding view of the outer face. Fig. 3 is a front elevation on a larger scale, showing the tablet alone and in the folded or closed condition. Fig. 4 is a 50 corresponding view showing the tablet opened to expose the addresses. Fig. 5 is a vertical section taken on the line 5—5 in Fig. 3. Fig. 6 is a transverse section on the line 6—6 in Fig. 5. Fig. 7 is a vertical section on a still larger scale, showing the upper portion of the tablet and corresponding

to Fig. 6. Fig. 8 is an elevation showing a portion of the outer face of the door adjacent to the tablet. Fig. 9 is an elevation showing a detail.

Similar letters of reference indicate the same parts in all the figures.

A is the door leading to the shop or office, shown as having a glass plate or panel A¹. The tablet is shown as mounted on one of the door-stiles near the glass panel and consists of a rectangular plate B and a cover C hinged thereon. The plate B is screwed to the stile and has an outwardly extending flange B² at the top. The cover C is flanged on all four sides and has ears C¹ at the lower end pivotally connected to corresponding lugs B³ on the plate to form a hinge upon which the cover may be folded upwardly upon the plate to inclose the latter. A spring tongue 75 B⁵ in the flange B² engages frictionally in a recess c in the upper flange of the cover and holds the cover in the closed position, as in Fig. 3.

Projections B⁴ B⁴ on the plate serve with 80 the flange B² in supporting a shaft D¹ carrying a leaf or wing D adapted to be folded upon the plate B and inclosed by the cover C. A spring D² on the shaft D¹ tends to turn the latter and swing the wing automatically outward into the plane of the plate when the cover is opened. The projections B⁴ B⁴ are formed one on each side so that the shaft D¹ may be mounted on either side in adapting the tablet for service on either 90 side of a door.

The face of the cover is in the form of a frame having a large central opening, and receives a glass plate or panel E protecting the normally outer face of a card F, which 95 with the glass is held by fingers on the side flanges of the cover, bent upon the margins of the card after the insertion of the latter and the glass. The wing D is also a frame and carries a card or sheet G.

H is a tube attached to the back of the upper portion of the plate B by fingers H¹ extending through suitable apertures therein and headed over upon the inner face of the plate; the tube is received in a hole α 105 bored through the stile. On the outer face of the door the hole is protected by a bushing A². The tube contains a rod H² projecting into the space within the cover and adjacent to the wing D, and the rod is held 110 yielding in this position by a helical spring inclosing the rod and abutting at one end

against the outer face of the plate B and at the other against a head H³ on the rod, thus permitting the latter to be forced inward by any slender implement, as a lead pencil, thrust into the hole a from the outer face of the door.

On that face of the card exposed to view through the glass E are instructions to the firemen and police and on the inner face of the card, protected from view when the tablet is closed, are the addresses or other information as to the location of the party or parties to be notified. The sheet G on the wing carries the same addresses on its inner face.

When it is necessary forcibly to open the door in case of fire or other unusual occurrence, the fireman or policeman may thrust a suitable implement into the hole a and by pressure of the rod H² against the wing D overcome the frictional engagement of the tongue B³ and recess c and release the cover C and permit it to swing downwardly aided by the opening effort of the wing, permitting the latter to turn and lie adjacent to the glass panel A¹ of the door, in which position, shown in Figs. 2 and 4, the addresses on the sheet G may be read through the glass panel of the door, or after the door is broken in, the entering parties may turn down the cover C from inside the room and expose the addresses on the inner face of the card F, in either case the addresses of the parties to be notified are immediately available.

The cover C is constructed to fit closely upon the plate and protect the cards from dust or smoke, and when in the closed condition to conceal the addresses, telephone numbers, or other information of a semi-private nature.

Modifications may be made in the forms and proportions, and parts may be used without the whole. The tablet may be mounted on doors having no glass panel, or on the door-casing or wall adjacent to the door, in such situations the wing D and tube H and its rod and connections may be omitted.

I claim:—

1. A plate attachable to a door, an open frame hinged to said plate, a card held in said frame with its opposite faces exposed

upon opposite sides of said frame, and means operable through the door to move 55 said frame on its hinge to expose the normally hidden face of said card.

2. A plate attachable to a door, an open frame for holding a card with its opposite faces exposed upon opposite sides of said frame, a hinged member interposed between said plate and frame, and means operable 60 through the door for moving said member to move said frame to expose the normally hidden face of the card. 65

3. A plate adapted to be secured to the inner face of a door-stile, a flange on said plate at its upper end, and a projection near its lower end, a shaft mounted in said flange and projection, a wing on said shaft, a spring on the latter tending to swing said wing from said plate, a cover hinged to said plate and inclosing said wing, means operable from the outer face of said door for opening said cover and releasing said wing, and a sheet on said wing carrying address instructions. 70

4. A plate adapted to be secured to the inner face of a door-stile, a flange on said plate at its upper end, and a projection 80 near its lower end, a shaft mounted in said flange and projection, a wing on said shaft, a spring on the latter tending to swing said wing from said plate, lugs at the lower end of said plate, a spring tongue formed in 85 said flange, a cover having ears at the lower end pivoted to said lugs, flanges on said cover constructed to inclose said plate and wing and having a recess adapted to be engaged by said tongue to hold said cover normally closed, said stile having an aperture therethrough, a tube on said plate extending into such aperture, a rod yieldingly mounted in said tube and arranged to strike and release said wing and cover, the latter having an opening in its face, a card exposed at such opening and bearing on its outer face notification instructions readable through such opening and address instructions on its inner face, and a sheet mounted 100 on said wing and bearing address instructions, such address instructions readable when said cover is open. 75

In testimony that I claim the invention above set forth I affix my signature.

CHARLES M. ROSE.
